UNITED STATES PATENT OFFICE.

FRANCIS J. GRUSS, OF SAN FRANCISCO, CALIFORNIA.

SANITARY SHIELD FOR DENTAL ENGINE HANDPIECES.

Application filed November 25, 1922. Serial No. 603,195.

To all whom it may concern:

Be it known that I, FRANCIS J. GRUSS, a citizen of the United States, residing at San Francisco, in the county of San Francisco and State of California, have invented new and useful Improvements in Sanitary Shields for Dental Engine Handpieces, of which the following is a specification.

The present invention relates to improvements in sanitary shields for covering the hand pieces of dental engines and has particular reference to a novel form of shield for angular hand pieces known as "contra-angle."

15 The primary object of the invention is to provide a shield of the character described which will prevent the hand piece of a dental engine from coming in contact with the mouth of the patient and prevent saliva from collecting or being deposited upon the hand piece during the use thereof, the shield being removable so that it may be taken from the hand piece and sterilized after each use of the hand piece.

25 Another object of the invention is to provide a shield of the character described which will not in any way interfere with the use of the hand piece and which will permit a removal and replacement of drill members without necessitating removal of the shield.

The invention further resides in the provision of a novel form of clamp for holding the shield in place.

35 The invention possesses other advantages and features some of which, with the foregoing will be set forth at length in the following description where I shall outline in full that form of the invention which I have selected for illustration in the drawing accompanying and forming a part of the present specification. In said drawing I have shown one form of the construction of my invention, but it is to be understood that I do not limit myself to such form since the invention as expressed in the claims may be embodied in a plurality of forms.

Referring to the drawing:

Fig. 1 represents a side elevation of the shield of my invention showing it as it would appear when in use.

Fig. 2 represents a top plan view of the shield as when in use, showing in dotted lines the position of the shield when open and ready for removal from the hand piece.

Fig. 3 is a top plan view of the clamp for holding the shield in place.

Fig. 4 is a cross section of the clamp.

In the drawing wherein I have illustrated one embodiment of the invention, 1 designates the angular hand piece of a dental drill engine, commonly known as the "contra-angle," in which the drill member 2 is extended at right angles to the hand piece and is removably held in place by means 3.

Fig. 5 is a top plan view of the shield of my invention comprising a tubular shell or casing formed of like halves 4 and 5, each half being substantially semi-cylindrical except at its outer end where it is provided with a right angular projection 6.

The projections 6 when the halves are moved together form a tubular portion to receive the right angular projection 7 of the hand piece. At the outer end of this projection 6, each half is recessed so that there will be provided an opening 8 through which the drill 2 extends. At their rear ends the halves are pivoted by vertical pivot members 9, there being ears 10 on the section 4 which overlie similar ears 11 on the section 5, through which ears the pivot members are inserted. By this arrangement the halves are adapted to swing apart horizontally to facilitate the attachment or removal of the shield and to close so as to form a tight close fitting cover.

There is provided an opening 12 on the upper side of the shield adjacent its forward end, said opening being provided by forming complementary recesses at opposed points in the halves 4 and 5. The opening 12 is immediately over the drill holding means 3 for the drill and of such size as will permit the operator to have access to and operate with the finger, said holding means whereby the drill may be removed or inserted without necessitating the removal of the shield from the hand piece.

As a means for holding the halves and the shield in proper position on the hand piece, I provide an arcuate or substantially semi-circular clamp 13, in the nature of a band, which is adapted to be slipped over the shell at the forward end and moved into position to extend over and close the opening 12. The clamping device has sufficient give or resiliency such that when it is moved into position over the opening 12, it will be under tension and hold the halves together. Suitable stop members 14 are provided on the

shield to limit the inward movement of the clamp. The free ends of the clamp are turned inwardly as at 16, and said inwardly turned portions engage in shallow grooves 17, formed in opposite sides of the shield. These grooves act as guides for the clamping member and serve as reinforcing elements for the halves of the shield. The clamping member is so shaped that it will conform closely to and substantially follow the contour of the shield except that there is provided a knob or protuberance 18 intermediate of its ends, said knob facilitating the gripping and handling thereof also the holding of the shield, when the latter is in place. It will thus be seen that the means for holding the halves together serve also as a closure for the opening 12.

In the particular form of shield shown, the body of the shield is straight from its forward end to a point adjacent the rear edge of the opening 12, and then extends at an obtuse angle. Preferably the shield is constructed of some light, durable metal which may be readily sterilized without injury, such as silver.

To attach the shield the hand piece is removed from connection with the dental engine, not shown, as is customary, and is placed with its inner end engaging between the halves at the pivoted ends of the latter, as shown in dotted lines in Fig. 2. The halves are then swung so that their opposed edges will meet and form a tight joint thus effecting a covering of the entire hand piece. The clamping member is then mounted on the upper side of the shield so that its in-turned ends 16 will engage in the grooves 17 and pushed rearward until it covers the opening 12 and engages the stop member. The hand piece is then connected with the dental engine, not shown, in the usual manner, and the instrument is ready for use with the hand piece such as would ordinarily be

brought into contact with the mouth of the patient and subject to saliva deposits now fully protected against contact with the mouth and such deposits of saliva.

The shield prevents the lubricating oil used in the instrument from running out into the mouth of the patient. This objection is encountered in the use of angular hand pieces and is entirely eliminated when my shield is used.

I claim:

1. The combination with the hand piece of a dental engine having an angularly extending portion at its outer end, a drill supported in said portion and means for holding the drill in the hand piece, of a sectional shield for said hand piece constructed to be moved into and out of position to encase the hand piece, said shield having an opening therein permitting access to and operation of the drill holding means, and means for holding the parts of the shield together upon the hand piece, said means acting as a closure for said opening.

2. The combination with the hand piece of a dental engine, of a sectional shield enclosing the hand piece and a member removably mounted upon the shield and movable thereon into and out of a position securing the sections of the shield in closed position, said shield having grooves extending longitudinally therein and portions on said member slidably engaging in the grooves.

3. The combination with an angular hand piece of a dental engine, a drill carried by said hand piece and means for holding the drill in place, of a sectional shield for said hand piece adapted to encase the hand piece, which shield is provided with an opening in one side thereof to permit access to and operation of the drill holding means and a closure for said opening.

FRANCIS J. GRUSS.
